UNITED STATES PATENT OFFICE.

WERNER SCHÄFFER, OF LAUPEN, NEAR BERN, SWITZERLAND, ASSIGNOR, BY MESNE ASSIGNMENTS, TO CHOCOLAT TOBLER HOLDING CO., AKTIENGESELLSCHAFT, OF SCHAFFHAUSEN, SWITZERLAND, A FIRM.

PROCESS FOR MAKING TYPE BARS.

Application filed October 13, 1923, Serial No. 668,383, and in Germany October 14, 1922.

This invention relates to typebars for typewriting machines and more particularly for line by line writing machines and a process for producing the same. The invention 5 relates especially to typebars with a row of different letters, numbers or signs thereon of substantially equal width, wherein the top of each letter, number or sign is adjacent to the bottom of the next. These typebars 10 are produced by casting a bar of metal on a row of types by the die casting process. In a preferred form of the process a row of existing type patrices is formed and an impression is taken therefrom with plastic material. A typebar is then cast on the said 15 impression. The types of which the rows of types are formed may be of any preferred kind, as for example cut or struck types, or types produced by a galvanoplastic process. 20 In another way the invention may be performed in the following manner: Any existing cast or engraved individual matrices are arranged in a row and placed in a mould, in which the typebar is cast by the die casting 25 process. The individual patrices or matrices may be spaced by individual spacing members or any other preferred spacing means.

The invention is shown for example in the 30 drawing, in which

Fig. 1 represents a row of matrices spaced apart by wedge-shaped spacing members and held together by a suitable holding means, the typebar being cast upon the 35 matrices and spacing members.

Fig. 2 illustrates a row of type patrices spaced by spacing members and held together in a suitable manner so as to form a row of patrices from which an impression is 40 taken with plastic material.

Fig. 3 is a transverse section of Fig. 2 on the line A—B, the lower end of the type being broken away.

Fig. 4 shows a top elevation of a typebar 45 formed on a row of matrices according to Fig. 1.

Referring to the drawing, 1 in Fig. 1 are individual matrices which are spaced apart by spacing members 2 wedge-shaped 50 at their top ends, the entire row of matrices and spacing members being held together by holding means in the form of terminal blocks 3. When a row of spaced matrices has thus been formed it is placed in a suit-

able mould and a typebar is cast on the said 55 row by means of the jet casting process. When the typebar has thus been cast the top wedge-shaped ends of the spacing members 2 form notches in the typebar 4. The notches are adapt'd to be engaged by alining 60 means for lining up rows of types on different typebars.

Fig. 2 illustrates a modified arrangement in which individual patrices in the form of types 5 and spacing pins or members 6 with trough-shaped tops are employed. The types 5 with their spacing members 6 are held together in a row by terminal holding members 7. When a row of spaced patrices has thus been formed, an impression is taken 70 therefrom with plastic material 8, this impression then forming a multi-type matrix upon which a typebar, indicated in Fig. 2 in broken lines, may be cast by the die casting process. The matrix 8 may consist of plaster of Paris, which, after the impression has been formed in it by the patrices, may be coated with graphite upon which a thin layer 75 of metal is deposited by electro-deposition. 80

I claim:

1. A patrix typebar for typewriting machines comprising a row of different die cast patrix characters of substantially equal width and with the top of one character disposed adjacent to the bottom of another. 85

2. A die cast patrix typebar for typewriting machines comprising a row of different characters of substantially equal width and separated one from another by means adapted to serve for aligning the typebar during the typewriting process, the top of one character being disposed adjacent to the bottom of another. 90

3. A die cast patrix typebar for typewriting machines comprising a row of different characters of substantially equal width and separated one from another by wedge-shaped notches, the top of one character being disposed adjacent to the bottom of another. 100

4. The process for producing typebars for typewriting machines, which process consists in forming a row of different matrix characters of substantially equal width, 105 wherein the top of one character is adjacent to the bottom of another, in providing projections between each two matrix characters 105

for producing notches between each two characters on the character-bearing side of the produced typebar, and in casting a typebar from the said row by the die-casting process.

5. In the process according to claim 4, the provision of wedge-shaped projections whereby wedge-shaped notches are produced on the character-bearing side of the typebar.

10 6. The process of producing typebars for typewriting machines, which process includes the forming of a row of different matrix characters by arranging different individual matrix characters in a row with interposed spacing means between each two matrix characters, said spacing means forming the said projections, the making of an

impression of said row of matrix characters in plastic material, and the casting of a typebar from said impression by the die-casting process.

20 7. The process of producing typebars for typewriting machines, which process includes the forming of a row of different matrix characters by arranging different individual matrix characters in a row with interposed trough-shaped means, the making of an impression of said row of matrix characters in plastic material, and the casting of a typebar from said impression by the die-casting process.

25 In testimony whereof I have affixed my signature.

WERNER SCHÄFFER.
